US00D851683S

(12) **United States Design Patent** (10) Patent No.: **US D851,683 S**
 Niven et al. (45) Date of Patent: **** Jun. 18, 2019**

(54) **DISPLAY SCREEN OR PORTION THEREOF WITH ICON**

(71) Applicant: **Dyson Technology Limited**, Wiltshire (GB)

(72) Inventors: **Ruth Niven**, Bristol (GB); **Leanne Joyce Garner**, Bristol (GB); **Andrew James Holden**, Cheltenham (GB); **Adam James Bates**, Oxford (GB)

(73) Assignee: **Dyson Technology Limited**, Malmesbury, Wiltshire (GB)

(**) Term: **15 Years**

(21) Appl. No.: **29/648,583**

(22) Filed: **May 22, 2018**

(30) **Foreign Application Priority Data**

Nov. 24, 2017 (EM) 004521524-0017

(51) LOC (11) Cl. **14-04**

(52) U.S. Cl.

(57) **CLAIM**

We claim the ornamental design for a display screen or portion thereof with icon, as shown and described.

DESCRIPTION

The single FIGURE is a front view of a display screen or portion thereof with icon showing our new design.

The broken-line perimeter illustrates a display screen or portion thereof and forms no part of the claimed design.

1 Claim, 1 Drawing Sheet
